ATTACHMENT FOR BOX-COVERING MACHINES

Martin V. Silby, New York, N. Y.

Application December 5, 1947, Serial No. 789,878

4 Claims. (Cl. 93—54.2)

1

The invention relates to attachments for box-covering machines of the type described in U. S. Patent No. 691,329, issued January 14, 1902, to Smith, and in my co-pending application in the United States Patent Office, bearing Serial Number 789,877, filed December 5, 1947.

The general object of the invention is to provide a novel and practical attachment for a machine of this type for the purpose of adapting the machine to operate to cover a box shell which is shaped like an octagonal prism.

A further object of the invention is to provide improved means in such attachment whereby the side-wall-forming parts of the cover blank may be accurately folded over the outside of the shell and positively affixed thereto.

A further object is to provide improved means in such an attachment whereby corner-lapping tabs of certain side-wall-forming parts of the cover blank may be accurately and positively affixed to the outer side-wall corners of the shell having the shape of an octagonal prism.

A still further object is to provide improved means for turning, or tucking, in the edges or margins of side-wall-forming parts of a cover blank which project above the top edges of the side-walls of a shell having the shape of an octagonal prism.

In the drawings:

Fig. 1 is a top plan view of one assembly of parts of the attachment of the present invention, being that assembly arranged to fold and affix corner-tabs of side-wall-forming parts of the cover blank to the outer side-wall corners of a shell having the shape of an octagonal prism. Only those several elements of the box-covering machine necessary to illustrate the mounting upon the machine of this assembly of parts of the attachment are shown in this figure. This figure shows the assembly of parts of the attachment in its normal or inoperative position.

Fig. 2 is a plan view of a flat, unfolded cover blank suited for covering a box shell having the shape of a right octagonal prism.

Fig. 3 is an isometric perspective view, from above, of the same cover blank folded into that shape obtaining when the blank is properly affixed to such a shell. In this figure the shell is absent for the specific purpose of illustrating the exterior and interior aspects of the folded cover blank.

2

Fig. 4 is a top plan view of another assembly of parts of the attachment of the present invention, being that assembly arranged to fold and affix certain, i. e., four, side-wall-forming parts of the cover blank (e. g., the cover blank of Figs. 2 and 3) to the outer side-walls of a shell of the shape described. This figure illustrates that stage of a box covering operation on a machine of the type described modified by the attachment of the present invention obtaining just after each alternate side-wall-forming part of a cover blank such as that of Figs. 2 and 3 has been folded upwardly and affixed to an alternate face of the outer side-wall of the shell. These alternate side-wall-forming parts of the cover blank are seen to be provided with corner-lapping tabs (cf. Fig. 2). The box covering machine itself is not shown in this figure.

Fig. 5 is a top plan view of another assembly of parts of the attachment of the present invention, being that assembly of parts arranged to fold and affix certain, i. e., four, side-wall-forming parts of the cover blank (e. g., the cover blank of Figs. 2 and 3) to the outer side-walls of a shell of the shape described. This figure illustrates that stage of a box covering operation on a machine of the type described modified by the attachment of the present invention obtaining just after each alternate side-wall-forming part of a cover blank such as that of Figs. 2 and 3 has been folded upwardly and affixed to an alternate face of the outer side-wall of the shell. These alternate side-wall-forming parts of the cover blank are not those having corner-lapping tabs. Thus the operational stage illustrated in this figure is subsequent to that illustrated in Fig. 4.

Fig. 6 is a top plan view of the operative edges, in normal, or inoperative position, of specially designed turn in, or tuck in, fingers (cf. U. S. Patents Nos. 753,524 and 1,424,316, both of which describe and show such fingers as ordinarily arranged for use where the box shell is a right parallelopiped) forming part of the attachment of the present invention.

Fig. 7 is a fragmentary perspective view of part of the shell having the shape of an octagonal prism, and shows part of a belt or strap usually provided for the purpose of holding the shell in shape during a covering operation.

Fig. 8 is a perspective view from above of a

finished box having the shape of an octagonal prism.

Fig. 9 is a fragmentary perspective view of a corner of a box such as that in Fig. 8 with portions of two adjacent side-wall-forming parts of the cover blank torn away to show a portion of corner-lapping tab of one such part (which is overlapped by the other part in the finished box) and also to show the belt, abovementioned, and the shell itself.

Fig. 10 is a top plan view of the assembly of parts of the attachment which is also illustrated in Fig. 1; however, in this figure (i. e., Fig. 10), the assembly is shown in its extreme operative position. Those elements of the box-covering machine appearing in Fig. 1 also appear in Fig. 10.

Fig. 11 is a fragmentary perspective view of a box such as shown in Fig. 8 in process of being covered. No parts of the attachment or box-covering machine appear in this figure. However, the figure is illustrative of the relative position of parts of the cover blank and shell at the operative stage illustrated in plan in Fig. 4.

Fig. 12 is a schematic, vertical, axial cross-section of the apparatus showing the relative positions of the various elements omitting the cross-hatching at the first level of the brushes and on the vertical shaft.

Fig. 13 is an enlarged detail view of the brush mounting.

Machines of the type described in U. S. Patent No. 691,329 are normally adapted to cover box shells having right parallelopipedal shape. The operation of such machines in covering box shells of this shape is briefly described in my co-pending application for United States patent mentioned above. The operation of the unmodified machine as well as its construction is so well known to those skilled in the art of covering boxes that herein I shall describe only enough of the operation and construction to enable one skilled in the art to understand the operation and method of mounting the attachment of the present invention.

Machines of type described comprise means for carrying a box shell, with the cover adhering to the bottom thereof, bottom-first through mechanism arranged to fold the projecting parts of the cover blank against the sides of the shell and to affix them thereon; and also to turn, or tuck in, with respect to the open top of the shell, the upwardly projecting parts of the cover blank, so that these parts may then be next folded into the shell and affixed to the inner sides thereof.

Preparatory to operation of the machine to apply a cover blank to a shell, the shell is placed, usually by hand, bottom-downward on the central portion of the flat cover blank, the latter having adhesive coating on its upper surface, i. e., the surface which is to be bonded to the shell itself in the box-covering operation. The shell, with the flat cover blank adhering to its bottom external surface, is then placed upwardly against a block fixed horizontally at the lower end of a vertically disposed plunger, the block having the shape and approximate dimensions of the inside of the shell and forming temporarily a core therefor, as well as a reinforcement therefor, to prevent its deformation during the covering operation.

In the drawings hereof I do not show the plunger, which is well known; I show a block 11, which is shaped like an octagonal prism instead of like a parallelopiped, as is usually the case.

The block 11 is seen in plan in Figs. 1, 4, 5, and 10; but the plunger is not even indicated in section.

In the machine, somewhat beneath the plunger mentioned above is another coaxial plunger having at its upper end a horizontally disposed plate. When the machine is set in operation the upper plunger descends, carrying the block, shell, and cover blank with it; when the under surface of the cover blank engages the upper surface of the plate the two plungers then descend as a unit with the plate, cover blank, shell, and block between them. Obviously the two plungers and the block and plate serve together as a means for positively holding the box-forming elements in proper position during the box-covering operation. The plate is usually shaped like the bottom of the shell; thus, in my attachment, I provide a plate having the shape of an octagon of dimensions substantially equal to those of the octagonal bottom of the shell involved.

The cover blank and shell are carried down between a pair of horizontally disposed opposing rollers which normally operate, in the unmodified machine, to fold upwardly and to affix to the sides of the shell oppositely projecting side-wall-forming parts of the cover blank. If such parts are provided with corner-lapping tabs means normally present on the machine next operate to fold such corner-lapping tabs around the side-wall corners of the shell and to affix such tabs. Next the cover blank and shell are carried down, further, between a similar pair of rollers set at 90° to the first pair for the purpose of folding and affixing the two remaining side-wall-forming parts of the cover blank. It will be obvious, of course, that the immediate foregoing refers to the operation of the machine in covering a parallelopipedal box shell. After all (four) side-wall-forming parts of the cover blank have been folded and affixed to the outside of the shell the edges of such parts projecting upwardly beyond the top of the side-walls of the shell are next folded over the tops of the side-walls of the shell and down into the shell, and affixed to the inner side-walls thereof. To accomplish this, after the outside of the shell has been covered, the block is withdrawn from the shell, while the box-forming elements, i. e., the cover and shell, are supported by the plate upon the lower plunger, and members known as turn in, or tuck in, fingers (cf. supra) advance centripetally, with respect to the shell, upon such edges, and bend them from a vertical disposition to a horizontal one; after such fingers are retracted the shell and block are again brought together, such action effecting a further (inward) folding of the edges and their fixation to the inside of the shell walls. The box is then, of course, complete, and by means well known in the art, is ejected from the machine, which is then ready for a next box-covering operation.

The plate is nowhere shown in the present drawings, but will be understood, in Figs. 1, 4, 5, and 10, to be just beneath the shell.

To facilitate understanding of the attachment of the present invention I now describe more particularly the structure and shape of the type of shell and cover blank relating to the type of box to be finished by the machine when modified by my attachment.

First, it may be mentioned, the machine operates only to cover a box shell and not to form the same during a box covering operation. Thus the shell is ordinarily preformed by hand before

the covering operation, and is also generally provided with a stay of some sort to hold it in shape prior to covering.

Fig. 8 shows, in perspective, a finished box in the shape of an octagonal prism. This shape is substantially the shape of the preformed shell. The shell blank is usually die cut and scored by machinery. In the case of a shell for a box having octagonal prismatic shape, the flat blank would roughly resemble an octagon; the central portion, presently to become the bottom of the shell, would be actually an octagon; the side-wall-forming parts would be rectangular tabs on each side of the octagonal bottom portion. Thus, of course, the blank would have eight such side-wall-forming parts or tabs. These being bent in a common direction at 90° to the bottom portion, a shell of octagonal prismatic shape would result; however, this shape would, of course, be unstable, and some sort of stay is desirable. A belt or strap, of width substantially equal to the side-wall height of the shell, and of length substantially equal to the periphery of the shell sidewalls, is usually, and preferably, placed over the shell to prevent the side-wall-forming parts from unbending and so deforming the shell.

In Fig. 7 I have shown, in a fragmentary perspective view, part of a belt- or strap-stayed shell having the shape of an octagonal prism. The belt, or strap, is designated as B, the shell itself as S. The belt B is usually made of the same material as the shell blank itself, say, paper board, and is usually formed by bending a strip of material so that the ends meet, abutting, and are stayed by an adhesive tab; in other words, a strip is usually given seven bends at equally spaced stations of position, so that the finished, stayed strip is a hollow octagonal prism.

It will be obvious that application of the cover to the shell operates further to reinforce and stay the shell.

The flat cover blank is shown in Fig. 2, and is designated C. The octagonal central portion of the blank is substantially equal in size and shape to the octagonal central portion of the shell blank plus the thickness of the surrounding belt B. The cover blank C is provided with eight side-wall-forming parts, each of which is larger in what may be called height than a corresponding side-wall-forming part of the shell blank, so that, in the finished box, the edges of the side-wall-forming parts of the cover blank C may be folded over the tops of the side-walls of the shell, as shown in Fig. 8.

Four of these side-wall-forming parts of the cover blank C are mere rectangles without corner-lapping tabs, and are designated 12, 12, 12, 12. The other four parts are provided with corner-lapping tabs, as seen in Fig. 2, and are designated 13, 13, 13, 13. That portion of each part 12 which, in the finished box, engages the outer surface of a side-wall of the shell, is designated 12a; similarly, the corresponding portion of any part 13 is designated 13a. That portion of any part 12 which, in the finished box, engages the inner surface of the shell, is designated 12b; similarly, the corresponding portion of any part 13 is designated 13b. Any corner-lapping tab is designated 13c, for such tabs exist only on parts 13. Thus it is seen in Fig. 2 that three species of fold or bend lines exist in the cover blank C. These are usually scored on the blank at the time the same is die cut to shape. The fold line between the central portion of the blank and any side-wall-forming part is designated as F₁; the

fold line of any part that corresponds to the top edge of a side-wall of the shell is designated F₂; and the fold line of any corner-lapping tab is designated F₃.

5 In a covering operation involving a shell S, with belt B, and a cover blank C, the preformed belt-stayed shell is bonded to the central (octagonal) portion of the cover blank in the usual manner; and the shell, with the cover blank adhering to its bottom, is placed upwardly against block 11, which enters the shell and forms a temporary core and reinforcement therefor.

10 However, as the shell S presents eight sidewalls at eight different directions from the center of the shell, the normal means provided on such machines for covering parallelopipedal boxes are not adapted for use with such a shell. However, it should be pointed out that at least four of the side-walls of the shell S may be positioned 15 in the directions normally assumed by said-walls of parallelopipedal shells. This is of importance in the operation of my attachment.

20 Thus, in mounting my attachment on such a machine I first remove the normal four-square block from the upper plunger and the normal four-square plate from the bottom plunger, all four rollers, and all four of the turn in fingers. I also remove, the means normally provided for 25 folding and affixing corner-lapping tabs.

25 In a box covering operation on such a machine the first folding and affixing operation with respect to side-wall-forming parts of the cover blank involves those parts having corner-lapping tabs. This, of course, is so that the next operation 30 may fold and affix these tabs so that in the third operation the remaining side-wall-forming parts may be affixed over such tabs and so render the finished box more uniform externally.

30 Thus, in the attachment of the present invention I mount upon the brackets provided on the machine as mounts for the first pair of rollers that assembly of parts illustrated in Fig. 4.

35 This assembly of parts comprises a frame, positioned horizontally on the machine beneath the upper plunger and centrally disposed with respect to the axis of the plunger, made up of two L-shaped members 30 and 31, and of other members more particularly described below. The member 30 is provided with slots 32, 33, and 34 to facilitate its attachment to the machine, as by bolts, such as 34a. Similarly, member 31 is provided with slots 32a, 33a, and 34a. The L-shaped members 30 and 31 are seen to be alike except that each is opposite hand to the other.

40 Attached to one arm of L-shaped member 30 is a bracket 35 projecting inwardly with respect to the frame. At the inner end of the bracket 35 is a pivotally mounted holder 36 for a brush 37. The brush 37 is prevented by means not illustrated, such as a convenient detent on bracket 35, from dropping out of the position illustrated in Fig. 4; but the brush may be raised. Also, attached to the corresponding arm of L-shaped member 31 is a bracket 38 projecting inwardly 45 with respect to the frame, and opposing bracket 35. At the inner end of bracket 38 is another pivotally mounted holder 39 for a brush 40. Brush 40 may be raised but not lowered from the position shown in Fig. 4. It will be seen in Fig. 4 that the ends of the filaments of these two brushes are in opposition across the center of the frame, and that the ends of the filaments of each brush are in a vertical plane.

50 Attached to the other arm of L-shaped member 30 is an adjustable bracket 41; and opposing 55

55

60

65

70

75

this bracket across the center of the frame is another adjustable bracket similar to bracket 41 except that the two brackets are rotated 180° with respect to each other. Bracket 41 may be variously positioned on the arm of L-shaped member 38, and locked thereon by means of a bolt 41a which passes through a slot 41b in said bracket. Adjustably mounted on bracket 41 so as to be variously positioned at 90° to the direction of motion available to said bracket is an arm 42 at the inner end of which is a pivotally mounted holder 42a for a brush 43. The bracket similar to bracket 41 on the corresponding arm of L-shaped member 38 across the center of the frame is designated 44. Bracket 44 may be variously positioned on the arm of L-shaped member 38, and locked thereon by means of a bolt 44a which passes through a slot 44b in said bracket. Adjustably mounted on bracket 44 so as to be variously positioned at 90° to the direction of motion available to bracket 44 is an arm 45 at the inner end of which is a pivotally mounted holder 45a for a brush 46.

Brushes 43 and 46 are prevented from dropping out of the positions illustrated in Fig. 4; but both brushes may be raised. It will be seen in Fig. 4 that the ends of the filaments of brushes 43 and 46 are in opposition across the center of the frame, and the ends of the filaments of each brush are in a vertical plane.

Now, it will be obvious that the four brushes may be adjusted so as to define, speaking with respect to the ends of their filaments, incompletely a four-square space through which the box-forming elements may be passed, and so that these brushes will operate to engage, fold upwardly, and affix to the shell each alternate side-wall-forming part of the cover blank C. Specifically, Fig. 4 illustrates that stage in the box covering operation obtaining just after this operation is complete. Notice that, with the block 11 and the surrounding box forming elements B, C, and S passing downward between the brushes, brushes 37, 40, 43, and 46 are respectively engaging and affixing side-wall-forming parts 13, 13, 13, 13 of cover blank C. Side-wall-forming parts 12, 12, 12, 12 are passing between the ends of the brushes and remain horizontal; also, the brushes have not folded and affixed the eight corner-lapping tabs 13c. The brushes are preferably so positioned that the respective planes of their filament ends are normally somewhat nearer the center of the frame than the outer surfaces of the side-walls of the shell will be when the box forming elements are passed between the brushes so that the filaments are slightly deflected as the elements pass by causing the brushes to sweep the side-wall-forming parts against the side-walls of the shell under tension.

After the box forming elements have passed through the frame illustrated in Fig. 4 it is then desired to fold and affix the corner-lapping tabs 13c of side-wall-forming parts 13, 13, 13, 13.

Machines of the type described are provided with a pair of horizontally disposed bars, oppositely positioned on the machine, and beneath and parallel to the first pair of affixing rollers. These bars are arranged to move horizontally toward each other a predetermined distance immediately after the box forming elements have passed between the first pair of affixing rollers for the purpose of carrying against the corners of parallelopipedal box shells blades or like members arranged to fold and affix corner-lapping tabs.

On these bars, which are designated, in Figs. 1

5 and 10, 20 and 21, I mount, in my attachment, that assembly of parts arranged to fold and affix, in one operation, the eight corner-lapping tabs of a cover blank C.

5 This assembly of parts of the attachment is seen in plan, in both Fig. 1 and in Fig. 10, the former showing the parts in normal, or inoperative position, and the latter showing the parts in extreme operative position. Fig. 1, therefore, illustrates 10 that stage of the box covering operation just immediately after the box forming elements have passed through the frame illustrated in Fig. 4, and immediately before the stage illustrated in Fig. 10. The assembly of parts for folding and 15 affixing the corner-lapping tabs strictly comprises two assemblies which are alike except that each is opposite hand to the other. Thus the description of that half of the entire assembly to the right in Fig. 1 or Fig. 10, given in detail, will serve, 20 in essence, as a description of that half of the entire assembly to the left in the figures.

In Figs. 1 and 10, at one end of bar 20 is an adjustable bracket 58 locked on said bar by means of set screws 59 and 60. Pivotally mounted at 25 58 on bracket 58 is an arm 54. That the effective length of the arm 54 may be varied a number of spaced holes 55 are provided near the end that is pivotally mounted on the bracket. It will be noticed 30 that the arm 54 is mounted on the underside of the bracket, which is to say, underneath the bar 20. At the inner end of arm 54 is a holder 56 for a brush 57.

At the corresponding, i. e., righthand, end of the bar 21 is an adjustable bracket 58 locked on 35 said bar by means of set screws 59 and 60. Pivotally mounted at 61 on bracket 58 is an arm 62. That the effective length of the arm 62 may be varied a number of spaced holes 63 are provided near the end that is pivotally mounted on the bracket 58. It will be noticed that the arm 62 is mounted on the topside of the bracket 58, which is to say, over the bar 21. At the inner end of 40 arm 62 is a holder 64 for a brush 65.

Pivots and slidably mounted at 66 on bracket 45 58 is a slotted bar 67; and similarly mounted at 68 on bracket 58 is another slotted bar 69. Bar 67 is mounted on the topside of bracket 58; however the bar is offset so that it may freely pass beneath the arm 62. Within a slot 70 in arm 50 62 rides a headed stud 71 fixed to and protruding upwardly from bar 67. The head of the stud 71 prevents the same from dropping out of the slot 70, and serves to link the arm 62 and the bar 67 together as a bridge not free to sag appreciably but free to assume a variety of positions in a horizontal plane.

Bar 69 is mounted to the underside of bracket 58; however the bar is offset so that it may pass freely over the arm 54. Within a slot 72 in arm 60 62 rides a headed stud 73 fixed to and protruding downwardly from bar 69. The head of the stud 73 (not visible) prevents arm 54 from sagging materially at its inner end, and likewise serves to link the arm 54 and bar 69 together as a bridge, which, however, is free to assume a variety of positions in a horizontal plane.

70 Arm 54 passes free beneath arm 62; bar 67 may pass over arm 54, and bar 69 may pass beneath arm 62, as seen in Fig. 10, the extreme operative positional view.

At the end of bar 67 away from the stud 71 is a holder 74 for a brush 75; and at the end of bar 69 away from the stud 73 is a holder 76 for a brush 77.

75 All four brushes are at the same level not-

withstanding the varying levels of the supporting elements, the individual shape of each holder being such as to compensate for the difference in level of the several supporting elements, i. e., the arms and bars.

That half of the assembly to the left in Figs. 1 and 10 may be an exact duplicate of the half to the right, described above. For this reason I designate like corresponding parts of the half of the assembly to the left in the figures by indices duplicating the reference numbers of parts described above, with an *e* following the numbers, thus: 50e, 51e, etc.

The parts of the entire assembly are positioned normally as shown in Fig. 1. As the box forming elements are passed beneath the frame illustrated in Fig. 4 into the middle of the assembly illustrated in Fig. 1, all side-wall-forming parts 13, of cover blank C, have been folded upwardly and affixed to their respective side-walls of the shell (i. e., strictly, such side-wall-forming parts 13 have been affixed to the outer surface of the belt B opposite such respective side-walls of the shell S). However, at this stage, none of the corner-lapping tabs 13c have been bent with respect to the related parts 13, as shown in Fig. 1.

When the box forming elements are positioned substantially as shown in Fig. 1 the two bars 20 and 21 operate, in machines of the type described, to approach each other at 90° to their respective axes. Fig. 10 shows the bars and the parts supported thereon in the position of farthest movement of the bars. As the bars 20 and 21 approach each other, the brush 57 at the end of arm 54, for example, approaches bar 21; however, as the stud 73 of bar 69 resists a movement of arm 54 in a direction normal to bars 20 and 21, bar 69 is also set in motion relative to bar 21. The end of bar 69 being slotted at the pivotal mount at 68 on bracket 58, as shown, the bar can both rotate slightly and move with arm 54. The operation tends, due to the angular relationship of the arm 54 and bar 69 and to the shape of slot 72, to cause stud 73 to ride into an end of slot 72 as shown in Fig. 10. Thus brushes 57 and 71 move toward each other as indicated in Fig. 1 by the arrows, and ultimately are positioned with respect to each other as shown in Fig. 10. In moving thus each brush sweeps a corner-lapping tab 13c of a side-wall-forming part 13, and folds the tab around the corner of the wall of the shell, or, strictly, around the bend of the belt relating to such corner, and so affixes the tab.

It will be obvious from the foregoing that the pair of brushes 65 and 74 operates similarly, as do the pairs 57e and 71e, and 65e and 74e. Thus, in one movement of the bars 20 and 21, all eight corner-lapping tabs of the parts 13 of the cover blank C are folded and affixed.

Fig. 1 shows all such tabs 13c unfolded; Fig. 10 shows them folded and affixed. Of course, at the stage illustrated in Fig. 10 the parts 12, 12, 12, 12 of the cover blank C still have not been disturbed.

After the affixing of the corner-lapping tabs the box forming elements are carried still farther downward by the machine to the position normally occupied by the second pair of affixing rollers. Here, in my attachment, I provide a pair of brackets, one each on the normal bracket provided for supporting one roller of such second pair. This arrangement is illustrated in Fig. 5, in plan, from above. I show four brushes 100, 101, 102, and 103, which are similar to the

brushes 37, 40, 43, and 46 of the frame illustrated in Fig. 4. The brushes 100 and 102 are respectively held by holders 104 and 105, which are pivotally and resiliently mounted on bracket 106, which, in turn, is adjustably mounted on that bracket for one of such second pair of affixing rollers to the left in Fig. 5; and the brushes 101 and 103 are respectively held by holders 107 and 108, which are pivotally and resiliently mounted on bracket 109, which, in turn, is adjustably mounted on the other bracket, i. e., that to the right in Fig. 5, for the other of such second pair of affixing rollers.

The brushes 100, 101, 102, and 103 are mounted, as shown, in Fig. 5, so as to engage the diagonally disposed side-wall-forming parts 12, 12, 12, 12 of the cover blank C. These brushes may not drop from the position shown in the figure, but, like brushes 37, 40, 43, and 46, may be slightly raised; the ends of the filaments of any brush (in Fig. 5) normally are in a vertical plane, such plane being at 45° to the corresponding plane defining the ends of the filaments of any of the brushes in Fig. 4. Preferably, also, the planes defining the ends of the filaments of the four brushes of Fig. 5 are somewhat closer to the center of the path of the box forming elements during the box covering operation than the outsides of the belt of the shell so that, as the box forming elements descend through the assembly shown in Fig. 5 the side-wall-forming parts 12, 12, 12, 12 are folded and affixed to the shell, or belt, with a sweeping motion under tension. The brush-holders of Fig. 5 may be pivotally and resiliently mounted in any of a variety of equivalent ways: in dotted lines, 110 indicates a compression spring related to holder 107, the holder 107 being pivotally mounted at 107a. The illustration of a brush holder in Fig. 13 may be taken as typical of all brush-holders in Figs. 4 and 5.

As the box forming elements pass through the assembly shown in Fig. 5 the side-wall-forming parts 12, 12, 12, 12 are folded upwardly and affixed to the shell, or belt, and each such part 12 overlaps two corner-lapping tabs 13c. In Fig. 9, a fragmentary perspective detail showing a corner of the finished box, with portions of two adjacent side-wall-forming parts 12 and 13 torn away so that the structure beneath may be seen, the overlapping of the corner-lapping tab 13c by part 12 is clearly illustrated.

After the box forming elements have passed through all stages of the box covering operation heretofore described, and illustrated serially in Figs. 4, 1, 10, and 5, in the order named, the condition of the box, as a whole, is then as follows:

All parts 12 and 13 have been engaged and folded upwardly by brushes, and all portions 12a and 13a of the parts 12 and 13 respectively have been affixed properly to the outside of the shell, and, of course, all corner-lapping tabs have been properly folded and affixed. But all portions 12b and 13b of the cover blank C now project vertically above the top edge of the shell. The next operation, obviously, involves the use of turn in, or tuck in, fingers.

As the machine itself is arranged to effect withdrawal of the block, e. g., 11, from the shell during the turning in, or tucking in, operation, it is necessary in applying my attachment to the machine merely to substitute for the normal fingers provided for handling parallellopipedon boxes other fingers specially suited to the shape 75 of box previously described.

Thus, as shown in plan and hardly more than schematically in Fig. 6, I substitute for two opposing fingers another pair of fingers 120 and 121 having the rectangular shape of fingers ordinarily used with parallelopipedal boxes but having a frontal length corresponding to that of one side of the octagonal prismatic box. For the other two fingers I substitute fingers 122 and 123 having faces shaped to accord with three consecutive sides of the octagonal prismatic box, as is clearly shown in the figure. These special fingers operate similarly to the ordinary fingers, except that fingers 120 and 121 engage each the edge of a part 13 of cover blank C, and, in moving centripetally with respect to the box forming elements, fold the portions 13b of these parts over the top edge of the shell and so dispose them horizontally; and at the same time, the fingers 122 and 123 engage each the edges of a part 13, and of two parts 12 of cover blank C, and, in moving centripetally with respect to the box forming elements, fold portions 13b and 12b of these parts over the top edge of the shell and so dispose them horizontally. The practice, in the art, of raising slightly the corners of two opposing pair of fingers so that they will override the edges of the other two opposing pair, is well-known. After the fingers are retracted, the block and box forming elements are brought together again, the entry of the block into the shell effecting a folding inwardly of all portions 12b and 13b, and the affixing of these portions to the inner surfaces of the side-walls of the shell. Then, of course, the box is complete.

The next operation of the machine, which is standard, is the raising of both coaxial plungers to original positions. At a certain stage the lower plunger is arrested in its ascent, at which stage ejectors force the completed box off the block; then the block with its upper plunger continues to ascend; and other ejectors throw the box out of the machine—that is to say, off the plate—to one side. When the completed box is passing upward through the brushes 100, 101, 102, and 103 (see Fig. 5) and the brushes 31, 40, 43, and 46 (see Fig. 4), these brushes are again engaged, and it is desirable that they be so mounted that they may be easily forced upward slightly and out of the path of the box by the top edges of the block or top edges of the completed box itself. In this respect the mounting of the brushes has been previously described. Of course the completed box does not engage, during its ascent, any of the parts illustrated in Figs. 1 and 10, as these parts have then returned to normal or inoperative position.

Fig. 11 is a fragmentary perspective detail of two corners and of one side and of parts of two adjacent sides of the box in process of being covered. No parts of the attachment or of the machine are shown here. Fig. 11 illustrates the condition of the box just after the box forming elements have passed through the frame illustrated in Fig. 4.

It will be understood, of course, that throughout, in the foregoing, while "shell" has been used to designate the folded shell blank specifically, from time to time, it has also been employed to designate the assembly comprising the specific shell S and the belt B as a unit. Of course, where a belt is used to hold the shell blank in shape, the side-wall-forming parts of the cover blank are exteriorly affixed not to the shell blank proper, but to the belt itself, and interiorly to the actual inner surface of the vertically disposed side-wall-forming parts of the shell blank. The

belt is a convenience; obviously the actual shell blank could be stayed by adhesive tabs at each of the eight corners. For the purposes of the present invention, the attachment is arranged to adapt a machine of the type described to apply a cover blank to a shell, of whatever construction, that has the shape of an octagonal prism.

I claim:

1. In an attachment for a machine arranged to cover a box shell presented bottom-first to the covering mechanism thereof, said shell having a flat cover blank adhering to the bottom thereof, and said attachment adapting the machine to cover a box shell having the shape of an octagonal prism, eight brushes, positioned in the path of said shell so as to engage side-wall-forming parts of said cover blank and to effect sweeping toward and affixing to said shell of said side-wall-forming parts, said brushes being arranged in groups of four at two levels so that the first group engages each alternate side-wall-forming part and the second group engages the remaining side-wall-forming parts.
2. In an attachment for a machine arranged to cover a box shell presented bottom-first to the covering mechanism thereof, said shell having a flat cover blank adhering to the bottom thereof, said attachment adapting said machine to cover a box shell having the shape of an octagonal prism, and said cover blank having eight side-wall-forming parts projecting outwardly beyond the bottom of said shell, eight brushes positioned in the path of said shell and of said eight side-wall-forming parts of said cover blank so as to engage said side-wall-forming parts and to effect sweeping toward and affixing to said shell of said parts, the filaments of said brushes being deflected by the bottom of said shell, and said brushes being arranged in groups of four at two different levels so that the first group engages each alternate side-wall-forming part of said cover blank and that the second group engages the remaining side-wall-forming parts, each such brush being pivotally mounted on said machine so that each may be moved out of the path of said shell when the latter moves relative to said brushes oppositely to the original direction of said shell.

3. In a machine for covering a box shell introduced downwardly therein bottom first with a cover blank having eight side-wall forming tabs four thereof having corner lapping tabs adhering to said bottom, an attachment adapting said machine to cover a box shell having the shape of an octagonal prism, said attachment comprising an upper frame with four brushes mounted thereon, and engaging and sweeping against certain side-walls of said shell during descent of said shell four of said side-wall forming tabs having corner lapping tabs: four pairs of movable brushes and means for moving said movable brushes into engagement with said corner lapping tabs for engaging and sweeping said corner lapping tabs against other side-walls of said shell; two opposing brackets each having mounted thereon two diagonally disposed brushes, said brushes engaging and sweeping against said other side-walls of said shell the other four side-wall forming tabs; and four turn-in fingers, two having straight edges and the other two having recessed edges composed of consecutive straight sections conforming to three consecutive side-walls of said shell.
4. In an attachment for a box covering machine, said attachment adapting the machine to

13

cover an eight-sided box shell having a cover blank adhering to the bottom thereof, said blank having eight side covering tabs four of which have corner lapping tabs, means for affixing four of said side covering tabs to said shell and a second means for affixing the other four of said side covering tabs to said shell, four pairs of movable brushes, and means for moving said movable brushes into engagement with said corner lapping tabs for engaging and sweeping said corner lapping tabs against certain side-walls of said shell after the first four of said side covering tabs have been affixed to said shell by said machine

5

14

and before the second four of said side covering tabs have been so affixed.

MARTIN V. SILBY.
